UNITED STATES PATENT OFFICE.

PHILIP FLORENZ AND JOSEPH MAGLUILO, OF OZONE PARK, NEW YORK.

DESIGN FOR A BIRDCAGE.

Application filed August 6, 1926. Serial No. 18,620. Term of patent 14 years.

To all whom it may concern:

Be it known that we, PHILIP FLORENZ and JOSEPH MAGLUILO, citizens of the United States, residing at Ozone Park, Long Island, New York, have invented a new, original, and ornamental Design for a Birdcage, of which the following is a specification, reference being had to the drawing accompanying this application and forming part thereof.

The figure is a perspective view of a birdcage, showing our design.

We claim:

The ornamental design for a birdcage, as shown.

PHILIP FLORENZ.
JOSEPH MAGLUILO.
